(57) **CLAIM**

The ornamental design for a basket rim weave, as shown and described.

DESCRIPTION

FIG. 1 is a perspective view of a basket rim weave showing my new design.;

FIG. 2 is a front elevational view of the basket rim weave of FIG. 1. The rear and side elevational views are identical to the front elevational view.

FIG. 3 is a top plan view of the basket rim weave of FIG. 1. FIG. 4 is a bottom plan view of the basket rim weave of FIG. 1.

FIG. 5 is a perspective view of a second embodiment of the basket rim weave.

FIG. 6 is a front elevational view of the basket rim weave of FIG. 5. The rear and side elevational views are identical to the front elevational view.

FIG. 7 is a top plan view of the basket rim weave of FIG. 5; and,

FIG. 8 is a bottom plan view of the basket rim weave of FIG. 5.

The broken line showing of a round basket, in FIGS. 1–4, and a rectangular basket, in FIGS. 5–8, is for illustrative purposes only and forms no part of the claimed design.
